UNITED STATES PATENT OFFICE

96,299

DESIGN FOR A CASE FOR COSMETIC MATERIALS

Octavia E. Clarkson, Santa Clara, Calif.

Application August 11, 1934, Serial No. 52,922

Term of patent 14 years

To all whom it may concern:

Be it known that I, Octavia E. Clarkson, a citizen of the United States, and a resident of Santa Clara, in the county of Santa Clara and State of California, have invented a new, original, and ornamental Design for a Case for Cosmetic Materials, of which the following is a specification, reference being had to the accompanying drawing, forming part thereof, wherein,

The drawing is shaded to represent contrasting colors.

I claim:—

The ornamental design for a case for cosmetic materials, substantially as shown and described.

OCTAVIA E. CLARKSON.
